(57) CLAIM

The ornamental design for a pet collar with camera, as shown and described.

DESCRIPTION

FIG. 1 is a perspective view of a pet collar with camera in full lines with a cat shown in broken lines representing environmental association matter being for illustrative purposes only and forming no part of the claimed invention.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view of the pet collar with camera; and, FIG. 7 is a bottom plan view thereof.
